UNITED STATES PATENT OFFICE

2,596,413 has been issued to Walter Cameron Kincaid

VENETIAN BLIND

Walter Cameron Kincaid, Pueblo County, Colo.

Application June 24, 1949, Serial No. 101,117

3 Claims. (Cl. 160—166)

1

This invention relates to improvement in Venetian blinds.

Venetian blinds are extensively employed in residences and office buildings and have been found to be very satisfactory for controlling light and vision.

The ordinary Venetian blind, in spite of its desirable qualities, has many objectionable features which it is the object of this invention to remedy.

It is the object of this invention to produce a Venetian blind that can be quickly and easily installed and which can be readily removed for cleaning and repair.

Another object is to produce a Venetian blind of such construction that when it is in fully open position it will obstruct vision and light as little as possible.

A further object is to produce a Venetian blind that dispenses with the cords now commonly used for tilting the slats and which also dispense with the usual cords for raising the lower end of the blind.

A still further object is to produce a Venetian blind that is normally held in fully extended position under spring tension which prevents it from swaying in response to air currents when the window is open.

A further object is to produce a Venetian blind that has a pivoted connection with the window at a point between its ends and in which that part above the said pivotal connection is constantly under spring tension and can therefore be adjusted to any position while the part below is in raised collapsed position.

Another object is to produce a Venetian blind of such construction that the slats can individually be quickly removed for cleaning and as quickly and easily replaced, providing means for the interchange of slats and effecting appearance variations.

A still further object is to produce a blind of such construction that the supporting tapes are replaced by open link chains which obstruct the light and vision less than tape.

A further object is to produce a Venetian blind that can be constructed entirely of metal and which can be removed as a unit for washing.

A still further object is to produce a Venetian blind in which there need be no fabric and which requires no pulleys or gears and which may be constructed of any suitable metal.

The above and any other objects that may become apparent as the description proceeds are attained by means of a construction and arrangement of parts that will now be described in de-

2

tail, for which purpose reference will be had to the accompanying drawing in which the invention has been illustrated and in which:

Figure 1 is a front elevation showing the blind in fully extended position and partly tilted;

Figure 2 is a view similar to that shown in Figure 1 but shows the lower end in raised or elevated position;

Figure 3 is a section taken on line 3—3, Figure 1;

Figure 4 is a section taken on line 4—4, Figure 2;

Figure 5 is a side elevation of the support and anchor strip taken on line 5—5, Figure 1;

Figure 6 is a side elevation taken on line 6—6 Figure 1, showing one of the blind supporting brackets, with the friction clutch in place, the pivot being shown in sections;

Figure 7 is a top plan view of the bracket looking downwardly through plane 7—7 in Figure 6;

Figure 8 is a section taken on line 8—8 Figure 1, showing the intermediate bracket and the operating tilt rail mechanism;

Figure 9 is a section taken on line 9—9 Figure 25 4; and

Figure 10 is a fragmentary perspective view showing the manner in which the slats are supported and longitudinally positioned.

In the drawing reference numeral 15 designates 30 an ordinary window frame having sides 16 and 17, top 18 and bottom 19, secured to the sides 16 and 17, adjacent their upper ends, are brackets 20 having each notch 21 in its upper edge, forming bearings for the pivots 22 at the ends of the 35 top tilt rail 23. The pivots, as shown, are formed by the ends of a rod 24 that is spot welded or otherwise attached to the under surface of the top tilt rail.

Attached to sides 16 and 17 at points about 40 midway between the top and the bottom of the window are brackets 25 having their lower edges provided with notches 26 that form bearings for pivots 27 attached to the under surface of the operating tilt bar 28, the latter is provided near 45 one end with a short handle 29. The lower end of the blind is formed by a slightly upwardly convex lifting rail support 30 having attached thereto a pivot bar 30a. Two pair of chains 31, constructed with open links in the manner shown 50 in Figure 10, are attached at their upper ends to the top tilt rail by means of short tension springs 32.

Attached to the inner surfaces of sides 16 and 17, near their lower ends, are guide brackets or 55 anchor bars 33 each of which has an edge pro-

vided with two or more narrow upwardly ranging notches 34 and the lower ends of the chains are attached to the lifting rail support 30 and are of such length with respect to the distance between the bottoms of notches 21 and 35 that when the ends of pivot bar 30a are positioned in notches 35, springs 32 will be under tension.

Brackets 25 are so positioned that when the ends of pivot bar 30a are positioned in notches 35 the ends of pivot bar 27 will be positioned in notches 26 but out of contact therewith so that the force exerted by springs 32 will be resisted entirely by notches 35 and pivots 30a. When pivots 30a are disconnected from notches 35 springs 32 move pivots 27 into engagement with the bottoms of notches 26, as shown in Figure 8; It is therefore possible to disconnect the lifting rail support and its pivots from notches 35 raise them and position them in notches 34 as in Figure 4. That position of the blind below brackets 25 is thus supported from notches 34. With the parts in the position shown in Figure 4 the operating tilt bar 28 and all parts above may be rocked the same as when the parts are positioned as shown in Figure 3.

The ends of pivot bar 30a are formed non-circular and of such size that when they are positioned in notches 34 they cannot turn and will therefore hold the lifting rail substantially horizontal forming a shelf on which the raised portions are supported at uniformly spaced intervals the two chains of each pair are joined by short sections of wire or chain 36 on which the upwardly convex blind slats 37 are supported, as shown in Figure 10. Slats 37 are provided at least on one edge with notches 38 that are positioned to receive cross wires 36 or chains 31 when the slats are tilted; this prevents the slats from moving longitudinally.

It will be observed that slats 37 rest on and are loosely supported by the cross links 36 and they can therefore be readily removed and replaced for cleaning.

Referring now to Figures 6 and 7 it will be seen that one pivot at the end of the top tilt rail has connected therewith a clutch or braking device comprising a spring 40 bent into an elongated U-shape and positioned with its bight enclosing fixed stationary pin 39 attached to window frame. The free ends of the spring are curved to embrace the pivot. The amount of friction can be regulated by screw 41. This braking device or clutch is adjusted to hold the top tilt rail in any position to which it may be adjusted by the operating tilt.

Attention is directed to the ease with which the blind assembly can be removed from the window and replaced. When the lifting rail support is released from its pivotal connection with notches 35 and the operating tilt rail released from its connection with brackets 25 the top tilt rail can be lifted from brackets 20. Brake spring 40 may remain attached to the pivot and removed from pin 39 thereby retaining the brake adjustment unchanged when the top tilt rail is replaced. The slats may be removed for cleaning by tilting them sufficiently to remove the notches from engagement with the chains or links and they may be readily replaced by a reverse action.

After the blind assembly has been put into position plate 42 is attached to brackets 20 and covers the top tilt rail and brackets 20 as shown in Figure 2.

The slats are selected of the proper length to fit the window to be covered and are each pro-

vided with notches or cutouts to span the ends of the crossties 36, which, as above explained, retain them in proper position under all working conditions and permits their ready removal for cleaning.

Chains 31 may be of the construction shown in Figure 10 or of any other suitable construction. The construction employing chains is important for the reason that their lengths remain constant and therefore the necessary adjustments will be retained, for example, the distance between pivots 22 on the top tilt rail and the ends of pivot bar 30a on the lifting rail must always be less than the distance between notches 21 and 35 so that, when the parts are in the position shown in Figure 1 the assembly will be under tension. It is also necessary that the distance between pivots 30a and 27 shall be slightly less than the distance between notches 26 and 35 to permit the entire assembly to be tensioned. It is further necessary that the normal distance between pivots 22 and 27 shall be somewhat less than the distance between notches 21 and 26 so that the part above brackets 25 will be under tension when the parts are in the position shown in Figures 2 and 4.

For single sash windows the operating rail 23 may be dispensed with and the tilting effected by rocking the lifting rail support 30.

I claim:

1. A window blind of the Venetian type for use in a window frame with vertical sides, the combination with said frame of a pair of brackets attached to the sides near their upper ends, a second pair of brackets attached to the sides near their lower ends the upper pair having notches on top, the lower pair being elongated and provided with notches in their lower ends and also along one vertical edge, a tilt rail having pivots resting in the notches in the tops of the upper brackets, a lift rail having pivots at its ends for engagement with the notches in the lower ends of the lower brackets, four tension springs attached in pairs to the edges of the tilt rail adjacent the ends thereof, a slat tilting member attached to the lower end of each spring with their lower ends connected with the lift rail in a manner to effect simultaneous equal angular tilting of the rails, a plurality of spaced slats supported in parallel relation between the tilting members, the length of the springs, the tilting members and the distance between the notches in the lower ends of the lower brackets and the notches in the upper brackets being greater than the distance between the pivots on the rails whereby the tension in the springs will be increased when the lifting rail is pivoted in the end notches of the lower brackets.

2. A window blind in accordance with claim 1 in which slats are wider than the distance between the tilting members and have their edges provided with notches for the reception of the tilting members, thereby holding the slats in longitudinally adjusted position, being removable without assembly change.

3. A window blind in accordance with claim 1 in which there is a third pair of brackets attached to the sides of the frame substantially midway between the upper and lower pair of brackets, said brackets having notches on their lower edges, and a bar carried by the lifting members, projecting beyond the ends of the slats for engagement in the notches in the last named brackets, the distance from the pivots of the

tilting rail to the rod being less than the distance between the notches in the first and the last mentioned brackets whereby the lifting members will be put under increased tension when the bar is in engagement with the last mentioned brackets.
